(57) **CLAIM**

The ornamental design for the lawn mower scraper tool, as shown and described.

DESCRIPTION

FIG. 1 is an isometric view of a first embodiment of the lawn mower scraper tool of the present invention.

FIG. 2 is the front elevation view thereof;

FIG. 3 is the rear elevation view thereof;

FIG. 4 is a side elevation view thereof;

FIG. 5 is an elevation view showing the other side thereof;

FIG. 6 is the top plan view thereof;

FIG. 7 is the bottom plan view thereof;

FIG. 8 is an isometric view of a second embodiment of the lawn mower scraper tool of the present invention.

FIG. 9 is the front elevation view thereof;

FIG. 10 is the rear elevation view thereof;

FIG. 11 is a side elevation view thereof;

FIG. 12 is an elevation view showing the other side thereof;

FIG. 13 is the top plan view thereof; and,

FIG. 14 is the bottom plan view thereof.
